SAFETY DEVICE FOR PUNCH PRESSES

William James Ipsen, La Crosse, Wis.

Application September 11, 1941, Serial No. 410,470

5 Claims. (Cl. 192—129)

This invention relates to safety devices for punch presses.

At the present time certain punch presses are provided with a spring-pressed dog which is designed to stop the press when the movable die or punch is in an uppermost position. However, this spring-pressed dog is not entirely satisfactory as frequently the press hesitates in its operation after being released for starting a cycle, and permits a person to insert a hand or finger beneath the die or punch. After hesitating momentarily, the press completes its normal cycle of operation with resultant injury to the operator or any work which may not be properly positioned relative to the dies. It is, therefore, an object of this invention to provide a safety attachment for a press which is correlated with the usual spring-pressed stop dog and which is movable with the latter to a latching or released position, but is spaced from the latter dog sufficiently so that if the latter dog should be shifted to a released position and the press should hesitate in its operation, the second or auxiliary stop dog will automatically stop the press before any damage or injury results.

A further object of this invention is to provide in combination with a punch press, a pair of circumferentially spaced apart stop dogs correlated with the flywheel and drive shaft for the press so as to permit the operator to stop the press before it completes its normal cycle of operation and after the press begins its normal cycle.

A further object of this invention is to provide a safety attachment which in the normal operation of the press will be inactive, being held in an inactive position with the normal stop dog, a sufficient length of time to permit the press to operate its normal cycle, but in the event the press consumes more than the normal time in starting its cycle of operation, the attachment will become active to stop further operation of the press, the press being subsequently releasable for completion of its incomplete cycle by depression of the pedal connected with the normal stop dog.

With the foregoing objects and others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a fragmentary side elevation of a

5 punch press having a safety device constructed according to this invention mounted thereon,

Figure 2 is a fragmentary front elevation partly broken away and in section of the safety device,

5 Figure 3 is a sectional view taken on the line 3—3 of Figure 2, and

Figure 4 is a view similar to Figure 3 with the safety device and the stop dog in released position.

10 Referring to the drawings the numeral 10 designates generally the frame of a punch press which is provided with a vertically movable die or punch member 11 operatively connected with a rotary drive shaft 12 which is journaled in the upper portion of the frame 10. A lower stationary die member 13 is disposed in a position for correlation with the movable die 11 for performing the desired punching or die operation.

15 The shaft 12 has mounted thereon a wheel 14 which is formed with a hub or boss 15. The wheel 14 is provided at a point outwardly from the shaft 12 with an opening 16 which in the present instance is square or rectangular in transverse section and constitutes a keyway for receiving a key or abutment 17. The hub 15 is also formed with a recess 18 communicating with the recess 17 so that the inner portion of the key or abutment 17 will be exposed inwardly from the inner face 19 of the wheel 14. A pivoted stop dog 20 is pivotally mounted on a pin or bolt 21 which engages an outstanding boss 22 which is fixed to the frame 10. The dog 21 is formed with a key receiving recess or cutout 23 and is also formed with an inner wall or flange 24 which is engageable against the inner end of the key or abutment 17 as shown in Figure 3.

20 The dog 20 is rocked downwardly on the pivot member 21 by means of a dog operating pull rod 25. The rod 25 is formed with a lower straight portion 26 and an upper offset portion 27. The upper end of the upper portion 27 is secured in the lower end of a link 28 by means of a pair of lock nuts 29 and 30. The link 28 is formed with a pair of spaced ears 31 which are pivotally secured to the dog 20 adjacent the free end thereof by means of a pivot bolt 32 engaging through the ears 31 and the lower portion of the dog 20. The dog operating member 25 is slidable through a U-shaped guide member 33 which has the bight 34 thereof secured as by fastening devices 35 to the frame 10. The dog 20 is constantly urged upwardly to a position in the path of the rotation of the key or abutment 17 by means of a pair of springs 36 and 37. An upper collar 38 is secured by means of a set screw 39 to the rod 25 and bears

against the upper end of the spring 36. The lower end of the spring 36 bears against the uppermost leg 40 of the U-shaped guide member 33. The lower spring 37 at its upper end bears against a collar 41 which is fixed by means of a set screw 42 on the rod 26 between the upper leg 40 and the lower leg 43 of the U-shaped member 33. The lower end of the spring 37 bears against the upper side of the lower leg 43.

The link 28 is formed with an opening 44 therethrough at a point below the ears 31 and the forward end of a steadyng link or arm 45 is pivotally mounted in the opening 44, being mounted on a pivot bolt 46. The opposite end of the link or steadyng member 45 is pivotally mounted on a pivot member 47 carried by an outstanding boss 48 which is fixed relative to the frame 10.

The operating means for the rod 25 is conventional and includes means whereby the rod 25 may be pulled downwardly so as to hold the dog 20 in a released position for a sufficient length of time in order to permit the abutment or key 17 to rotate relative to the dog 20. The wheel 14 and the shaft 12 are adapted to rotate in the direction of the arrow 49 as viewed in Figure 1, rotating in a counterclockwise direction. It has been found in the operation of the press with the use of the stop dog 20 that when the dog 20 is shifted to a released position the shaft 12 does not immediately rotate at the desired speed and this hesitation in the rotation of the shaft 12 frequently has the effect of damaging the work or permitting the operator of the press to insert a finger or hand between the movable die 11 and the stationary die 13 thus causing injury to the operator.

In order to prevent the shaft 12 from completing a revolution thereof in the event the shaft hesitates in its movement, I have provided a second or safety dog 50 which is disposed in a position substantially ninety degrees from the dog 20. The dog 50 is pivotally mounted on a pivot member 51 carried by an outstanding boss 52 which is fixed relative to the frame 10. The dog 50 is similar in every detail to the dog 20, being provided with a recess or bill 53 within which the abutment or key 17 is adapted to engage and also is provided with a flange 54 engageable against the inner end of the abutment or key 17.

In order to provide a means whereby the safety dog 50 may be automatically shifted to a released position simultaneous with the shifting of the dog 20 to a released position, I have provided a link 55 which is pivotally mounted on a pivot member 56 carried by an outstanding boss 57. The boss 57 is fixed relative to the frame 10. The lower stop dog 20 has secured thereto or formed integral therewith an upwardly and obtusely extending arm 58. The lower end portion of the link 55 is pivotally secured to the arm 58 by means of a pivot member 59. The upper portion of the link 55 is formed with an elongated slot 60 within which a pin 61 carried by the dog 50 slidably engages.

In the use and operation of this safety device in the normal operation of the press through one complete cycle, the shaft 12 will make one complete revolution and the movable die 11 will move downwardly and then upwardly. When the shaft 12 operates in the normal manner and the stop dog 20 is moved to a released position by downward pull on the dog operating member 25, the speed of rotation of the shaft 12 is sufficient to permit the abutment 17 to pass the safety dog

50 before the two dogs 20 and 50 are returned to a locking position. After the abutment 17 passes the safety dog 50, the two dogs 20 and 50 will move to the positions shown in Figures 1 and 3. In Figure 4, the two dogs 20 and 50 are shown in the released position which is the beginning of the punching cycle.

However, in the event the shaft 12 does not start its rotation for performing the normal punching cycle, or in other words, hesitates in its initial rotation, the time period consumed during which the abutment 17 is released from the dog 20 until the abutment 17 reaches the safety dog 50 is sufficient to permit the dog operating member 25 to move the two dogs 20 and 50 to the locking position shown in Figures 1 and 3. In this one-quarter turn of the shaft 12 and the abutment 17, the die member 11 has only completed a portion of its downward movement so that in the event any work is misplaced between the two dies 11 and 13 or in the event the operator of the machine inadvertently inserts a hand or the like between the two dies, the safety dog 50 will stop the shaft 12 and the downward movement of the die 11 before any damage is done either to the work or the hand or arm of the operator. In the event the safety dog 50 is engaged by the abutment or key 17 as shown by the dotted line position 17a, the key or dog 50 may be shifted to a released position coactive with the movement of the dog 20 by downward pull on the dog operating member 25. In other words, in the event the safety dog 50 is effective due to the hesitancy in the rotation of the shaft 12, it is necessary for the operator of the machine to exert a second pulling operation on the dog operator 25 in order to permit the shaft 12 to complete its punching cycle. The safety dog 50 is so positioned on the press 10 as to be effective only on the downward movement of the movable die 11 as it is on this portion of the punching cycle that any damage may be done to either the work or the operator if the operator should inadvertently insert a hand or finger beneath the movable die. The mounting of the safety dog 50 on the press will not affect the normal operation of the press, but only affects the operation of the press when the operation is subnormal.

What I claim is:

1. In combination a punch press including a rotatable element and a manually releasable pivoted stop member normally biased to a position in the path of said element for stopping rotation of said element, a second pivoted stop member spaced from said first stop member for stopping said element after the latter is released from said first stop member, said stop members having spaced apart pivot axes, and means connecting said stop member with said first stop member for simultaneous operation with the latter.

2. In a punch press provided with a manually releasable spring-pressed stop member; a safety attachment comprising an auxiliary stop member disposed in a position spaced from said first stop member, and a linkage connecting said stop members together for simultaneous movement to either released or operative position, said first stop member normally effecting a stoppage of the press at the completion of each cycle of operation, and said second stop member effecting a stoppage of the press after beginning of a cycle of operation in the event the starting period of a cycle consumes more than the normal period of time.

3. In a punch press, a rotatable abutment car-

ried by said press, a stop dog, means pivotally mounting said dog on the press in a position for engagement with said abutment, an operating member connected with said dog, means engageable with said operating member constantly urging said dog to a position for engagement with said abutment, a second stop dog, means pivotally mounting said second dog in a position for engagement with said abutment at a point spaced from said first dog, and means connecting said dogs together for simultaneous operation, said second dog being so spaced from said first dog as to permit passage of said abutment upon normal rotation of the latter but to arrest rotation of said abutment upon delayed starting thereof.

4. In a punch press having a releasable spring-pressed stop dog for stopping rotation of the drive shaft at the end of each punching cycle and subsequently releasing the drive shaft for one complete revolution of the latter to perform a punching cycle, said shaft having an abutment fixed thereto for engagement with said stop dog;

5 a safety attachment for stopping rotation of said shaft in the event the shaft fails to immediately start rotation upon movement of said stop dog to a released position, said attachment comprising a safety dog member, means pivotally mounting said member on the press at a point circumferentially spaced from said stop dog in a position for engagement with said abutment, a connecting link pivotally connected to both of said dogs for effecting operation of said safety dog simultaneously with said stop dog, and means engageable with said link intermediate the ends thereof pivotally mounting said link on the press.

15 5. A safety attachment for a punch press provided with a spring-pressed pivoted stop dog engageable with a rotary abutment; said attachment comprising a safety dog, means pivotally supporting said safety dog in circumferentially spaced relation with respect to said stop dog, and means connecting said safety dog with said stop dog for operation of said safety dog constantly with and by said stop dog.

WILLIAM J. IPSEN.
